UNITED STATES PATENT OFFICE.

ERNEST O. FREDERICS, OF NEW YORK, N. Y., ASSIGNOR TO E. FREDERICS, INC., OF NEW YORK, N. Y., A CORPORATION OF NEW YORK.

CLIP.

Application filed February 3, 1925. Serial No. 6,531.

This invention relates to an improved type of clip capable of general use, but particularly adapted for use by hair dressers in connection with the permanent waving of hair.

One of the objects of this invention is that of providing a clip the parts of which may readily be locked against movement and retained in such condition, but which, when desired, may also be unlocked with facility.

A further object is that of constructing a device of the character stated which will firmly grip without injury to the hair or other substance or material disposed between its jaws.

An additional object is that of constructing a clip the parts of which will not readily be broken or disarranged, and which will additionally efficiently accomplish the purposes for which it is intended, aside from the fact that a clip embodying the improved construction of the present invention may be readily manufactured and assembled with facility.

Other objects of the invention will in part be obvious and will in part appear hereinafter.

The invention accordingly comprises the features of construction, combination of elements, and arrangement of parts which will be exemplified in the construction hereinafter set forth, and the scope of the application of which will be indicated in the claims.

For a fuller understanding of the nature and objects of the invention reference should be had to the following detailed description taken in connection with the accompanying drawings, in which:

Fig. 1 is a side elevation of a clip, embodying one form of construction within the terms of the present invention and showing the jaws in locked position;

Fig. 2 is a view similar to Fig. 1, but showing the parts in released position;

Fig. 3 is an edge view of the clip;

Fig. 4 is a view similar to Fig. 3, but showing the outer ends of the jaws; and

Fig. 5 is a sectional view of the device, illustrating the same as used in connection with hair waving.

It will be noted in the illustrated embodiment that a pair of jaws is utilized which are pivotally connected as at 14. One of these

jaws includes a single sheet of material 10, and the second of the same embraces a pair of plates 11 and 28, which are spaced from each other. The inner or adjacent edges of the jaws are curved to provide gripping portions, as at 12, 13, and in order to move the jaws towards each other, i. e., into gripping position, the outer end of the jaw 10 may be extended to provide a handle 15, while the similar ends of the plates 11 and 28 are also extended as at 16—29, in order to provide a second handle.

With a view to guiding the movements of the jaws and retaining the same against an accidental release a locking mechanism is utilized, and it is preferred that this mechanism include pawl and ratchet members. Thus, the jaw which includes the plate 10 may be extended as at 17 and have its outermost edge provided with a series of teeth 18 to provide a ratchet. As a consequence, the extension 17 will enter the space between the plates 11 and 28 upon the handles 15 and 16—29 being moved towards each other, and in order to properly guide the movements of the parts the edges of these plates may be struck out to provide guiding-lips 30 and 31 at the point adjacent which the end of the extension 17 will enter. A pawl is associated with the second jaw, and this pawl in the present instance includes a body 21 adapted to cooperate with one of the teeth 18 in order to lock the parts. The pawl 21 forms a part of a lever 20, which is disposed and movable within the space extant between the plates 11 and 28 and is pivotally mounted therein as at 19, the lever being extended beyond this point of pivotal support as at 22, at which point it is acted upon by a spring 23 anchored as at 24 and 25 between the plates last mentioned, it being further observed that the inward movements of the pawl are preferably limited by a stop 26 which may form a part of the plate 11. It will be obvious that the lever 20 may be extended to provide a handle 27 similar to the handles 15 and 16—29, in order to effect a deliberate retraction of the pawl.

In use it will be appreciated—reference being had to the art of treating hair—that a strand of hair 33 may be coiled around a core or rod 32 and enclosed within jackets or tubes 34 and 35, the latter of which pref-

erably extends to a point adjacent the scalp of the person whose hair is being treated. The jaws, which are separated to an extent even greater than that indicated in Fig. 2, are now brought to a position in which their gripping edges enclose the tube 35, and an operator, by bringing two of his fingers to bear upon the outer surfaces of the handles 15 and 16—29, may move these jaws to a position at which they will firmly grip the outer surface of the tube between their edges 12 and 13. The operator may thereupon release the handle portions, and the parts will remain in the position to which he has thrown them by virtue of the lock structure provided for this purpose.

During the movements of the jaws towards each other the parts will be efficiently guided, and the movements of the plates 20 limited to a single plane. Likewise, when it is desired to release the jaws it is not necessary to spring the same axially in different directions, but, rather, an operator, by simply moving the handles 27 and 16—29 25 towards each other by pressing his fingers upon the outer faces of these handle portions, will effect a retraction of the pawl 21, and, incident to the inherent tendency of the tube 35 and the strand of hair within 30 the same to expand, the jaws will fly open. In connection with the operation of the device it is to be noted that the clip will not pull the hair or injure the same, due to the fact that its movable parts are effectually 35 housed to prevent the hair or any material gripped thereby from being caught by this mechanism. It will also be understood that when the parts are to be released they will do so virtually in an automatic manner, it 40 being unnecessary to jerk the device, with consequent discomfiture to the person whose hair is being treated.

From the foregoing it will be appreciated that the objects of this invention are accomplished, and since certain changes may be made in the above construction, and different embodiments of the invention could be made, without departing from the scope thereof, it is intended that all matter contained in the 45 above description or shown in the accompanying drawings shall be interpreted as illustrative and not in a limiting sense.

It is also to be understood that the following claims are intended to cover all of the generic and specific features of the invention herein described, and all statements 50 of the scope of the invention which as a

matter of language might be said to fall therebetween.

Having described my invention, what I 60 claim as new and desire to secure by Letters Patent is:

1. A clip including a pair of pivotally connected jaws, means to lock said jaws in gripping position, and a pair of radial handle members carried by one of said jaws and movable one toward the other to release said locking means. 65

2. A clip including a pair of movably connected jaws, a handle on each of said jaws for moving the same in gripping position, means operative in response to said movement to lock said jaws in said position, and a handle associated with said means and arranged for cooperation with one of the 75 aforesaid handles for releasing said locking means.

3. A clip including a pair of movably connected jaws each comprising a strip of metal formed with a gripping edge and bent at 80 one end to provide a handle, means to lock said jaws in gripping position, and a handle associated with said means and movable adjacent one of the aforesaid handles to release said locking means. 85

4. A clip comprising a pair of movably connected jaws, one of said jaws comprising a pair of members spaced from each other to provide a recess, and the other of said jaws being formed with ratchet teeth, a member pivotally mounted within said recess, and a pawl carried by said pivotally mounted member and arranged for cooperation with said teeth to lock said jaws in operative position. 95

5. A combined clip and scalp shield including a pair of movably connected jaws, means pivotally mounted on one of said jaws and arranged for cooperation with the other jaw to lock said jaws in gripping position and shielding means for said locking means carried by the first jaw and extending beyond the inner edge thereof. 100

6. A clip, including a pair of movably-connected jaws, one of said jaws comprising a pair of members spaced from each other, means extending into said space for locking said jaws against movement with respect to each other, one of the ends of each of said members being extended to provide a common gripping portion. 105

In testimony whereof I affix my signature.

ERNEST O. FREDERICS.
